CLAIM

The ornamental design for a portable handheld radio, as shown and described.

DESCRIPTION

FIG. 1 is a front right and top perspective view of a portable handheld radio in accordance with the present invention.

FIG. 2 is a left side elevation view of the portable handheld radio of FIG. 1.

FIG. 3 is a right side elevation view of the portable handheld radio of FIG. 1.

FIG. 4 is a front elevation view of the portable handheld radio of FIG. 1.

FIG. 5 is a rear elevation view of the portable handheld radio of FIG. 1.

FIG. 6 is a top plan view of the portable handheld radio of FIG. 1.

FIG. 7 is a bottom plan view of the portable handheld radio of FIG. 1; and,

FIG. 8 is an exploded front right and top perspective view of the portable handheld radio of FIG. 1.

Broken lines are used to illustrate portions of the portable handheld radio that form no part of the claimed design. The thicker broken lines in FIG. 8 show a bracket that embraces the separated parts and form no part of the claimed design.

1 Claim, 5 Drawing Sheets
